Patented Aug. 17, 1915.

UNITED STATES PATENT OFFICE.

WILLIAM C. BAUER, OF NEENAH, WISCONSIN, ASSIGNOR OF ONE-HALF TO JAMES ROBERT CARL JENSEN, OF NEENAH, WISCONSIN.

PAPER-MAKING-MACHINE SLICE.

1,150,328.

Specification of Letters Patent. Patented Aug. 17, 1915.

Application filed March 26, 1914. Serial No. 827,459.

To all whom it may concern:

Be it known that I, WILLIAM C. BAUER, a citizen of the United States, residing at Neenah, in the county of Winnebago and 5 State of Wisconsin, have invented a new and useful Paper-Making-Machine Slice, of which the following is a specification.

My invention consists of forming the slice bars of more than the usual number of sections instead of the usual two pieces for allowing of the vertical adjustment of the several sections, at such a distance above the making wire as the density and flow of the pulp requires for making an even thickness 10 of paper. To an inexperienced person it would naturally be supposed that if the slices were at a uniform distance above the wire entirely across the machine, that a sheet of paper would be produced of a uniform and 15 even thickness. Such however is not the uniform result as all experienced paper makers know, owing to the variations in the density and flow of the paper pulp stock, and various devices have to be resorted to by the 20 machine tender to produce a sheet of even thickness, such as hanging a sheet of paper over the slice bars and letting it hang down upon the apron side and be drawn under the slice where the paper is running too thick, or 25 sometimes an obstruction is placed between the flow box and slices for changing the direction of the flow as the thickness of paper being run off requires. In the paper making 30 machines of a few years ago of a width of six feet more or less, the usual two piece slice 35 bars were sufficient for controlling the thickness of the paper, but with machines of nearly or quite double that width, some other means is required, and by forming the 40 slices of an additional number of sections, facilities are provided for gaging the thickness at numerous points along the slices.

My invention is shown in the accompanying drawing, in which,—

Figure 1 is an elevation of a slice bar embodying my invention. Fig. 2 is a plan of the slice as it appears in position across the machine. Fig. 3 is an end elevation thereof. Fig. 4 is a vertical section upon the line *a*, *a*, 45 of Fig. 2, and showing two sections secured together. Fig. 5 is a vertical section upon 50

the line *b*, *b*, of Fig. 2, as the sections appear in looking toward the right.

Similar numerals and letters indicate like parts in the several views.

55

1, indicates the end section of the slice bar formed of a suitable metal, having the end flange 2, into which the bolt 3 is tapped for securing the slice bar to the deckle frame, (not shown,) and a bracket 4, secured upon 60 the upper edge with bolts 5, and which bracket is provided with the vertical adjusting screw 6, and jam nut 7. A slot 8, is made through which a bolt 9, can be inserted for clamping two sections together between its nut and head, and a bracket 10, which may be integral with the section 1, and is provided with an adjusting screw 11 and jam nut 12, for adjusting said section 65 vertically, with reference to an adjoining 70 section.

The description thus far describes the construction of the usual slices formed of two sections.

My improvement consists of making the 75 end sections nearly one fourth of the length of the distance between the deckle frames and then inserting three sections 1^a, more or less according to the width of the machine, which are lapped upon each other and upon 80 the two end sections and bolted together in a manner similar to that in which the two end sections have been lapped and bolted together. Each of the intermediate sections is provided with brackets 10^a, adjusting 85 screws 11^a and jam nuts 12^a, and with a slot 8^a and bolt 9^a. With these five sections, (more or less,) facilities are provided, by means of the several short sections, for adjusting the slice bar at various points in its 90 length as the density and flow of pulp requires, whereby an even thickness of the sheet can be produced, notwithstanding the density and flow of the paper stock may vary.

95

Having described my invention, what I claim and desire to secure by Letters Patent, is,—

1. A slice bar for a paper making machine adapted to be mounted above the making wire and to extend across said wire from one deckle frame to the other and to be se- 100

cured thereto, composed of more than two sections, each section having means for connecting it to another section and for adjusting it vertically.

5. A slice bar for a paper making machine composed of two comparatively short end sections and one or more intermediate sections, means for securing the sections to-

gether side by side between opposite deckle frames and each section having means for ¹⁰ its vertical adjustment relative to the making wire.

WILLIAM C. BAUER.
